UNITED STATES PATENT OFFICE.

GILES MOORE, OF FRANKFORT, INDIANA.

FUSE.

1,113,038.

Specification of Letters Patent.

Patented Oct. 6, 1914.

Application filed October 11, 1913. Serial No. 794,645.

To all whom it may concern:

Be it known that I, GILES MOORE, a citizen of the United States, residing at Frankfort, in the county of Clinton and State of Indiana, have invented a new and useful Fuse, of which the following is a specification.

The present invention relates to improvements in fuses, one object of the invention, being the provision of a fuse, in which the fuse wire is normally held at the desired tautness regardless of the temperature to which it is exposed, and also by means of which the same may be readily renewed when burned, thus permitting the employment of the holder and the tensioning device by the simple introduction of a new fuse wire.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a side elevation of the complete fuse. Fig. 2 is a vertical central sectional view thereof. Fig. 3 is a cross section taken through the fuse tube from above the spring as viewed in Fig. 2.

Referring to the drawings, the numeral 1 designates the shell or cartridge, which is provided with the venting aperture 2, the lower cap 3 and the upper cap 4 being detachably connected by means of the respective bands 3' and 4' so that the parts within the shell or cartridge may be readily had access to for renewal and repair. The caps 3 and 4 are provided with the alining and

holding lugs 5 and 6 respectively, of usual structure. Connected to the lower cap 3 centrally thereof is an apertured lug 7, 45 which constitutes a supporting means for the spiral spring 8, the upper terminal 9 of which is connected to the lower end of the resistance or fuse wire 10, the upper end of said fuse wire being connected to the 50 hooked terminal 11 of the plate 12, which is connected to and depends from the under side of the cap 4. By this means, the spring 8 retains the desired tautness upon the fuse 11, regardless of the surrounding temperature. It is also apparent that when the fuse 10 burns, or is otherwise broken that the same may be readily renewed by properly looping and connecting the respective ends thereof to the terminal of the spring 8 60 and the hook 11. By this means, the shell 1 and the remaining parts are not necessarily useless when the fuse is burned out as is the case with the fuses generally employed.

What is claimed is:

A fuse, comprising a tubular case of insulation, two metal disks, one sealing each end of the case, a fixed apertured lug carried upon the inner side of one disk, a fixed hooked lug carried upon the inner side of 70 the other disk, a coiled spring having one terminal connected to the apertured lug, and a fuse wire connected to the other terminal of the spring and having a loop fitting over the hooked lug, whereby the spring holds 75 the wire taut.

In testimony that I claim the foregoing as my own, I have hereto affixed my signature in the presence of two witnesses.

GILES MOORE.
